FLUSH VALVE

James A. Sloan, River Forest, and James J. Swartz, Berwyn, Ill., assignors to Sloan Valve Company, Chicago, Ill., a corporation of Illinois

Application February 17, 1958 Serial No. 49,680

Term of patent 14 years

(Cl. D91—3)

Fig. 1 is an end elevation view of a flush valve embodying our new design;

Fig. 2 is a side elevation view thereof;

Fig. 3 is an end elevational view thereof taken from the right of Fig. 2;

Fig. 4 is a top plan view thereof; and

Fig. 5 is a bottom plan view thereof.

The dominant features of our design reside in the portions shown in full lines.

We claim:

The ornamental design for a flush valve, substantially as shown and described.
